United States Patent Office

Des. 175,859
Patented Oct. 18, 1955

175,859

PAD HOLDER

Jacob S. Sherman, Chicago, Ill., assignor to Park Sherman Company, Chicago, Ill., a corporation of Illinois

Application January 27, 1955, Serial No. 34,269

Term of patent 7 years

(Cl. D74—1).

FIG. 4

FIG. 1

FIG. 2

FIG. 3

Fig. 1 is a top plan view of a pad holder showing my new design;

Fig. 2 is a side elevational view thereof;

Fig. 3 is a rear elevational view; and

Fig. 4 is a perspective view thereof as it appears with the cover in raised position.

The pad shown in dotted lines in Figs. 2 and 4 is for illustrative purposes only.

I claim:

The ornamental design for a pad holder, as shown and described.
